RIFLE ATTACHMENT

Thomas Henry Bailey, Kingsport, Tenn.

Application May 19, 1933, Serial No. 671,924

1 Claim. (Cl. 42—77)

This invention relates to firearms and has for the primary object, the provision of an attachment adapted for any type of shotgun to provide in combination with the latter a rifle so that a hunter may have in a single unit both a shotgun and a rifle, placing the hunter to better advantage when hunting due to the fact that either the shotgun or the rifle may be used to meet varying hunting conditions as they arise and the attachment is of such a construction that it will not interfere with the use of the shotgun and may be readily detached therefrom when desired.

With these and other objects in view this invention consists in certain novel features of construction, combination and arrangement of parts to be hereinafter more fully described and claimed.

For a complete understanding of my invention, reference is to be had to the following description and accompanying drawings, in which

Figure 1 is a side elevation illustrating a shotgun with my invention applied thereto.

Figure 2 is a fragmentary sectional view taken on the line 2—2 of Figure 1.

Figure 3 is a view similar to Figure 2 showing the ejector removing an empty shell from the barrel of the attachment.

Figure 4 is a view similar to Figure 3 showing the bolt occupying a firing position with the ammunition arranged in the barrel of the attachment.

Figure 5 is a fragmentary sectional view illustrating a slot in the barrel of the attachment for accommodating the finger piece of the bolt.

Figure 6 is a fragmentary side elevation illustrating the attachment and showing the finger piece of the bolt operating in a slot in the forestock of the gun.

Figure 7 is a view similar to Figure 6, however, showing the opposite sides of the gun and disclosing the trigger and finger piece of the safety latch.

Figure 8 is a sectional view taken on the line 8—8 of Figure 1.

Figure 9 is a sectional view taken on the line 9—9 of Figure 1.

Figure 10 is a plan view illustrating the bolt.

Figure 11 is a plan view illustrating the firing pin.

Figure 12 is a fragmentary sectional view illustrating the connection between the bolt and the firing pin.

Figure 13 is a sectional view taken on the line 13—13 of Figure 2.

Figure 14 is a fragmentary side elevation partly in section illustrating the rifle barrel.

Figure 15 is a fragmentary sectional view illustrating a bracket for connecting the rifle barrel to the forestock.

Figure 16 is a fragmentary plan view illustrating the same.

Referring in detail to the drawings, the numeral 1 indicates a conventional type of shotgun to which my invention is applied and includes the shoulder stock 2, breech 3 and barrels 4, the latter being connected to the breech 3 by a forestock 5 similar in construction to the conventional type of forestock now employed on shotguns except that it is adapted to receive and support the attachment for the shotgun so that the gunner may have a rifle in combination with the shotgun.

A rifle barrel 6 of any desired caliber is supported near the rear end of the barrel 4 within a chamber 7 formed in the forestock 5. The barrel 6 has an extension 50 which abuts the lug 51 securing the forestock to the gun, thus providing resistance to the impact of firing. The rifle barrel extends parallel and in a plane below the barrels of the shotgun and has its forward end fitted in a clamp 8 which forms part of a bracket secured to the barrels of the shotgun by screws 9 passing through slots 9'. The slots provide for range adjustment horizontally while the thickness of the hanger cares for perpendicular range adjustment.

The rifle barrel 6, forwardly of the forestock, is provided with a firing chamber 10 and, adjacent said chamber, is provided with an ammunition slot 11 to permit ammunition to be placed in the chamber 10 and extracted therefrom, the shell being discharged exteriorly of the barrel by a bolt type ejector which will be hereinafter more fully described. A bolt 12 is slidably mounted in the rifle barrel in rear of the firing chamber and is of cylindrical formation to slidably support a firing pin 13. A pin 14 slidably connects the bolt with the firing pin so that they may have a limited sliding movement relative to each other. The firing pin is of hollow formation with one end closed by an integral wall carrying a pointed projection 15 to impinge upon and explode the cap of the ammunition in the firing chamber, a coil spring 17 being interposed between the end wall of the firing pin and the pin 14 for normally urging the firing pin towards the firing chamber. It must be understood that the pointed projection 15 may be arranged for rim firing although it is shown arranged for cen-

ter firing. A finger piece 19 is fixed to the bolt 12 and extends through a slot 20 in one side of the barrel 6, said slot having lateral branches 21 to be occupied by the finger piece 19 when the bolt is to be held against endwise movement. A set bolt 22 is secured to the bolt 12 and operates in a slot 23 in the barrel and also extends into the chamber of the forestock. The firing pin is provided with a slot 24 aligning with the slot 23 in the barrel and a corresponding slot in the bolt 12' to be engaged by a sear 25 for the purpose of holding the firing pin in a cocked or firing position. The sear is pivotally mounted, as shown at 26, within the chamber of the forestock and is engaged by a spring 27 to normally urge the head 28 of the sear through the slot 23 into engagement with the slot 24 of the firing pin when moved into firing position through the manipulation of the bolt. The rear end of the sear engages a plunger type trigger 28' mounted in a cup 29 carried by a closure plate 30 located on the opposite side of the forestock from the finger piece 19 of the bolt. The trigger is spring pressed by a spring 31 to retain the trigger in operative position.

The forward end of the bolt carries spring pressed and pivotally mounted ejectors 32 to engage the rim of the shell when in the firing chamber so as to extract it on the rearward movement of the bolt and discharge it through the slot 11.

35 A safety catch 33 is slidably mounted on the closure plate 30 to engage a shoulder 34 of the head 28 of the sear for locking the same against pivotal movement and release of the firing pin from firing position. A finger piece 35 is connected to the safety catch and located on the closure plate adjacent the trigger so that the person using the firearm can readily lock or unlock the sear.

40 In operation, the rifle is loaded by moving the bolt rearwardly, thereby uncovering the ammunition slot 11 so that a projectile may be inserted into the firing chamber. The bolt is then moved
45 forwardly to bring the forward end thereof in engagement with the cap end of the projectile. The bolt when moved rearwardly to permit the loading of the rifle carries with the same the firing pin which is automatically engaged and held in a rearward position by the sear, thereby placing the rifle in firing position when the bolt is returned forward for holding the projectile in the firing chamber. During the use of the gun when loaded, the safety catch is in engagement with the shoulder of the sear until it is desired to fire the rifle when the safety catch is released from the sear. When the bolt is moved rearwardly,
50 the set screw 22 is carried against the safety catch
55

which is thereby moved into engagement with the sear, as shown in Figure 3. When the bolt is moved forwardly, the catch will remain in engagement with the sear, and it will not be released until the finger piece 35 is manipulated. To fire the rifle the trigger 28 is depressed, rocking the sear on its pivot and disengaging the head thereof from the firing pin, allowing the latter to travel forwardly under the influence of the spring 17 and carry the pointed element 15 into engagement with the cap of the ammunition with force sufficient to cause an explosion.

From the foregoing description it will be seen that the device or attachment may be easily and quickly applied to a shotgun and removed therefrom when desired. The removal will necessitate the removing of the rifle barrel from the forward hanger and the disconnection of the forestock from the breech. An ordinary forestock may be substituted in lieu of the removed forestock attachment when desiring to use the shotgun in the ordinary manner. The shotgun when equipped with the rifle attachment gives the user the advantage of a shotgun combined with a rifle so as to meet all occasions of hunting that may arise as sometimes it is more advantageous to employ a rifle for killing the game than a shotgun. The device is to be constructed as lightly as possible with the assurance of safety so as not to materially increase the weight of the shotgun.

While I have shown and described the preferred embodiment of my invention, it will be understood that minor changes in construction, combination and arrangement of parts may be made without departing from the spirit and scope of my invention, as claimed.

Having described the invention, I claim:

A gun attachment comprising a forestock having a chamber and slots communicative with the chamber and opening outwardly through opposite walls of said forestock, a plate secured to the forestock to close one of the slots, a barrel extension mounted in the chamber and having slots aligning with the first-named slots, a barrel integral with the extension and having a firing chamber communicative with the extension, a breech block slidable in the extension, a finger piece carried by the breech block and extending through one of the slots of the forestock by way of one of the slots of said extension, a firing means 45 slidable in said breech block, a sear for holding the firing means in cocked position and pivotally mounted to said extension and arranged in the slot of the forestock closed by said plate, a slideable button type trigger carried by said plate and engageable with the sear, and a safety catch for the sear and carried by the plate. 50 55 60
